[57] CLAIM

The ornamental design for a truck body, as shown and described.

DESCRIPTION

FIG. 1 is a rear perspective view of a truck body showing our new design;

FIG. 2 is a front perspective view thereof;

FIG. 3 is a side elevational view thereof, the opposite side being a mirror image of that shown;

FIG. 4 is an end view thereof;

FIG. 5 is a top plan view thereof;

FIG. 6 is a rear perspective view of a second embodiment of a truck body showing our new design;

FIG. 7 is a front perspective view of the truck body of FIG. 6;

FIG. 8 is a top plan view of the truck body of FIG. 6; and,

FIG. 9 is an end view of the truck body of FIG. 6.

The broken lines shown in all drawing views are for illustrative purposes only and form no part of the claimed design.
